ATTORNEY

UNITED STATES PATENT OFFICE.

CHARLES G. NESSLER, OF NEW YORK, N. Y.

HAIR-WAVING DEVICE.

Application filed July 30, 1926. Serial No. 125,916.

This invention relates generally to an electrical heater apparatus for use in waving or curling hair and more particularly to a current regulating device structurally combined with the electrical heater apparatus.

In United States Letters Patent No. 1,544,593, there is described and claimed an electrical heater apparatus for use in waving hair, which includes a vertical post or standard supporting in a laterally extending position at its upper end a frame member from which a plurality of electrical heater devices are suspended. The heater devices are arranged to individually treat a strand 15 of hair which is wound upon a suitable core member and inserted into the tube for the desired treatment. The heaters may be raised or lowered individually or all together to suit the conditions of operation. 20 The standard has a base member supplied with casters so that the apparatus as a whole may be wheeled about from chair to chair as occasion requires. In conducting hair waving operations with apparatus of the general 25 type described, which has gone into universal and extensive use, it has been found that in different localities there are variations in the voltage of the electric current supplied and since variation in voltage results in a corresponding variation in the 30 heat developed in the coils of the individual heaters, it is necessary to supply some form of current or voltage regulating means. It is accordingly an object of the present invention to provide a current regulating means 35 as a part of the heater apparatus referred to.

The invention comprises the use of a rheostat coil preferably wound directly on and in insulated relation to the standard or post which forms a part of the main framework of the heater apparatus. A slideable contact member is mounted on a conducting rod and arranged to be moved along the rheostat coil to make contact with different 45 windings thereof in accordance with the position of the slide with relation to the length of the coil. One of the lead in conductors includes the rod or bar on which the slide is movably mounted and also includes 50 the slide member itself and a variable number of windings in the coil corresponding to the position of the slide member thereon.

A cylindrical shell or housing surrounds the coil in spaced apart relation thereto and 55 preferably disposed in an eccentric relation with respect to the standard or post on which

the coil is mounted in order to provide for sufficient space or clearance in which to mount the movable slide member. The casting or housing is provided with a longitudinal slot through which the slide member extends for access by the operator. The housing is also provided with perforations in its side wall to provide a ventilating or cooling action and preferably some form of current 60 reading device is mounted on the upper end of the housing for convenience of the operator in setting the slide to produce the desired temperature conditions in the heating devices. 70

Other features of the invention will be hereinafter described and claimed.

In the drawings, in which a preferred embodiment of the invention has been selected for illustration:

Figure 1 is a view in side elevation with parts broken away of a heater apparatus for use in waving hair, which is equipped with a current regulating device embodying the invention; 80

Figure 2 is a view in horizontal section and on an enlarged scale taken on the line 2-2 of Figure 1;

Figure 3 is a view in side elevation and on an enlarged scale of a portion of the apparatus shown in Figure 1 and taken at right angles to the position of the parts shown in Figure 1. 85

Referring to the drawings for a more detailed description of the invention, in Figure 90 1 there is shown an electrical heater apparatus of the type described which includes a post or standard 5 mounted on a laterally extending base member 6 provided with suitable casters or rollers 7 to provide for moving the apparatus about from place to place. The upper end of the standard 5 is equipped with a telescopic section 8 which terminates in a laterally extending upper portion 9 having depending therefrom a framework 10 100 from which are suspended a series of electrical heaters 11 used in treating hair. 95

The reduced section 8 of the standard 5 which is adapted to be vertically adjusted within the lower and hollow standard section 105 5 is provided with a coil 12 formed of suitable resistance wire and wound on a layer of insulating material 13 which immediately surrounds the enclosed section of the standard 8. Disk or plate members 14 and 15 110 provided respectively at the lower and upper ends of the coil 12 are mounted in eccentric

relation to the standard 8 and provide upper and lower closure members for a housing or casing member 16 which is mounted in enclosing relation to the coil 12 and the included portion of the standard or post 8. The end plate members 14 and 15 serve also to support a rod or bar 17 on which a slideable contact member 18 is mounted for movement longitudinally of the coil 12. The slideable contact member 18 makes contact with adjacent windings of the coil 12 and thereby provides a means for varying the number of the windings of the coil 12 which are included in the circuit path of current passing through the device. For this purpose the rod or bar 17 and the coil 12 are included in part in the circuit path, the portion of each which is included being determined by the position of the sliding contact member 18 on the bar 17 and the coil 12. The contact member 18 is provided with a handle 19 projecting through a slot 20 in the side wall of the housing 16 for the convenience of the operator in using the device.

It will be seen that the housing or casing 16 is mounted in an eccentric relation with respect to the coil 12 and the included section of the standard 8. The eccentricity thus produced provides for a substantial space or clearance 21 on the side of the coil 12 in which the sliding contact member 18 is arranged to operate. The housing or casing 16 is preferably provided at its upper and lower ends with openings 22 which serve to ventilate and control the temperature of the device. A switch 23 or other current controlling means is mounted on the housing at a place convenient for the operator.

Preferably a current measuring device, such as a volt meter 24 having a wall 25 provided with an elongated horizontal sight opening 26 therein and pointer or marker 27 movably mounted back of the sight opening, is mounted on the upper end of the casing at a point easily read by the operator in order to assist in adjusting the position of the slideable contact member 18 to provide the desired temperature condition in the heaters 11. No scale is provided, the attendant merely being required to take care that the marker 27 is brought into alignment with the enlargement 28 in the sight opening or slot 26.

A conductor cable 29, having a plug connector 30, is provided for connecting the heater apparatus described to any convenient wall outlet.

It will be seen that a current controlling device has thus been provided in combination with a heater apparatus of the general type described, which enables operators in different localities to procure the desired standard and constancy of temperature and to adjust the apparatus in accordance with the various voltages used in different localities in order to bring about the desired same-

ness of temperature required for the most effective hair treating operation. By using a current regulator or voltage adjustor of the type described, variations in voltage covering as much as twenty-five units may be compensated for to produce the same degree of heat. The coil 12 is wound in practice to effectively operate on an apparatus employing twenty or more individual heaters 11 on current of one hundred and ten volts or thereabouts.

What I claim is:—

1. In an electrical heater apparatus for use in treating hair, said apparatus including a post, heating means supported by the post, a resistance coil wound about the post, an electrical conductor connection for supplying current to the heating means, and means for connecting different proportions of the coil into the conductor connection to regulate the current supplied to the heaters. 80

2. In an electrical heater apparatus for use in treating hair, a framework including a vertical post, heating means supported by the post, an electrical conductor connection through which current is supplied to the heating means, a resistance coil wound on the post, a slideable contact member mounted to be moved along the coil to make contact with different windings thereon, and said coil and contact member being included in the conductor connection to regulate the current supplied to the heating means. 90

3. In an electrical heater apparatus for use in treating hair, a framework including a vertical post, a laterally extending heating means supporting member at the upper end of the post, an electrical conductor through which current is supplied to the heaters, a resistance coil wound on and insulated from said vertical post, a slideable contact member adapted to be moved along the coil for contacting engagement with different windings thereof, and said coil and slideable contact member being included in said conductor, whereby to regulate the current passing therethrough to the heating means. 100

4. In an electrical heater apparatus for use in treating hair, a framework including a vertical post, a laterally extending heating means supporting member at the upper end of the post, an electrical conductor connection through which current is supplied to the heating means, a resistance coil wound on and insulated from said vertical post, a slideable contact member adapted to be moved along the coil to make contact with different windings thereof, a tubular casing enclosing the coil and spaced therefrom, said casing being provided with an elongated slot through which the slideable contact member extends for manipulation by the attendant, said coil and slideable contact member being included in said electrical conductor connection. 115

nnection whereby to regulate current passing to the heating means, and a switch device for the conductor connection mounted on the casing.

5. In an electrical heater connection for use in treating hair, a vertical post, a laterally extending heater supporting member at the upper end of the post, a portable base member for the post extending in the same lateral direction that the heating means supporting member extends, an electrical conductor connection through which current is supplied to the heaters, a resistance coil wound about a portion of said vertical post, a slidable contact member adapted to be moved along the coil to make contact with different windings thereof, a tubular perforated sheet metal casing surrounding the coil in eccentric relation thereto, said slid-
able contact member being operable in the space provided by the eccentric disposition of the casing, said casing being provided with an elongated slot through which the contact member extends, a current indicating device on the casing, and a switch de-

vice for the conductor connection mounted on the casing.

6. In apparatus used in waving hair, a portable base, an upstanding post mounted upon the base, heating means supported by the post, a coil wound upon a portion of the post, a movable contact to coact with the coil, and a circuit including the coil and contact to supply current to the heating means.

7. In apparatus used in waving hair, an upstanding post, heating means supported by the post, a coil wound upon a portion of the post and extending longitudinally thereof, a casing mounted upon the post and extending longitudinally thereof and surrounding the coil, a contact member movable longitudinally of the casing to engage with the coil, and a circuit including the coil and contact member to supply current to the heating means.

In testimony whereof, I have hereunto set my hand.

CHARLES G. NESSLER.
